SAFETY CONTROL MEANS FOR OIL
BURNERS

John Stahl, Stelton, Carl Reed, Newark, and Hans Fischer, East Orange, N. J., assignors to The Fairlie & Wilson Coal Company, Newark, N. J., a corporation of New Jersey

Application April 14, 1937, Serial No. 136,774

9 Claims. (Cl. 158—28)

This invention relates, generally, to improvements in safety control means for oil burners; and the invention has reference, more particularly, to a novel electro-mechanical means adapted to automatically arrest operation of an oil burner in the event of any failure of its operating elements to properly function, or in the event of the interruption or if improper delivery of fuel thereto.

This invention has for an object to provide novel electro-mechanical means to govern the operation of the fuel pump actuating motor of an oil burner apparatus so that delivery of fuel to the burner nozzle cannot occur unless and until the electrical ignition means serving the burner nozzle is operative.

This invention has for another object to provide an electrical-mechanical control system comprising a main circuit serving the electrical devices of the burner apparatus, said main circuit including a normally closed tripable cut-out or safety switch; that part of said main circuit which serves the fuel pump motor including a normally open motor control switch in series with said cut-out or safety switch; that part of said main circuit which serves the electrical ignition means including a transformer, the primary winding of which is also in series with said cut-out or safety switch; an electro-mechanical trip means for said cut-out or safety switch, the circuit of which includes a trip control switch also in series with said cut-out or safety switch; thermostatic actuating means for closing said motor control switch; and means governed by normal flow of fuel to the nozzle of the burner apparatus for opening said trip control switch.

Other objects of this invention, not at this time more particularly enumerated, will be understood from the following detailed description of the same.

An illustrative embodiment of the invention is shown in the accompanying drawings, in which:—

Fig. 1 is a side elevation of the tubular mixing chamber or gun of an oil burner apparatus as equipped with the novel electro-mechanical safety control means according to this invention, this view also including a wiring diagram showing the electrical circuits employed; Fig. 2 is a horizontal sectional view of the same; Fig. 3 is in part a side elevation and in part a vertical sectional view of the same; and Fig. 4 is an enlarged fragmentary detail view of the clutch connection between the thermostatic actuating means and the motor control switch carrier. Fig. 5 is a simplified wiring diagram showing the electrical circuits of the safety control means according to this invention.

Similar characters of reference are employed in the hereinabove described views, to indicate corresponding parts.

Referring to the drawings, the reference character 5 indicates the tubular mixing chamber or gun of an oil burner apparatus. Disposed within the interior of said mixing chamber or gun, to extend axially therein, is the fuel burner pipe 6, the same being provided at its outer end with a suitable burner nozzle 7 which is located within the outer open end of said mixing chamber or gun 5. The outer end of said mixing chamber or gun 5 is provided with a mixer ring 8 having internal spiral vanes 9 which serve to swirl the air, delivered through the mixing chamber or gun 5, about the burner nozzle 7 so as to mix such air with the fuel such as oil, discharged from the burner nozzle, and thus produce the necessary combustible mixture of oil and air which is ignited and discharged into the fire-box or combustion chamber of the furnace or the like which is served by the oil-burner apparatus. The burner pipe 6 is supported within the mixing chamber or gun 5 by a suitable standard 10 affixed to the latter. Said standard 10 is provided with oppositely disposed laterally and upwardly offset bracket members 11 and 12 in which are respectively supported electrode holders 13 and 14 from the forward ends of which extend electrical ignition electrodes 15 and 16. Said ignition electrodes are provided with inwardly offset free end portions 17 and 18 having spark gap forming terminals 19 and 20 located adjacent to and overhanging the burner nozzle 7. Also provided in connection with said standard 10, to extend longitudinally above the supported burner pipe 6 and between the bracket members 11 and 12 is a slideway member 21. Movable longitudinally on said slideway member 21 is a slide plate 22, the movements of which are guided by slots 23 formed therein which ride on guide screws 40 affixed to said slideway member 21. Affixed to the forward end portion of said slide plate 22 is a spark gap insulator, the same comprising an inverted T-shaped member formed by an upstanding central portion 25 bordered by oppositely extending horizontal portions 26 which respectively underlie the offset free end portions 17 and 18 of the ignition electrodes 15 and 16. At its forward free end, said central portion 25 is provided with a wedge-shaped extremity 27. The spark gap insulator may be made of any suitable electrical insulating material, such e. g. as steatite. When the oil burner apparatus is not operating, said spark gap insulator occupies a forwardly projected position so that the front end part of said 55

central portion 26 thereof is projected between the spark gap terminals 19 and 20 of the ignition electrodes (see Fig. 2), thus preventing arcing therebetween when current is initially served thereto until other starting operations assure proper delivery of oil to the burner nozzle for operative discharge therefrom.

Suitably mounted on an external side of the mixing chamber or gun 5, so as to be preferably disposed in a vertical plane, is a panel 28. Extending through said panel 28, and through the adjacent wall of the mixing chamber or gun 5, is a metallic casing 29. This casing 29 is provided with an annular shoulder portion 30 which abuts the outer face of said panel 28. Extending rearwardly from said shoulder portion 30 and through the panel is a threaded boss 31 which receives a keeper nut 32, whereby the casing 29 is affixed to the panel 28. Said casing 29 is provided at its outer end with a forwardly projecting tubular extension 33. One of the electrode holders, as 18, is provided at its rearward end portion with a diametrically enlarged chambered member 34. The rearward end portion of said casing 29 passes inwardly through the wall of said chambered member 34 so as to extend transversely into the interior of the latter. Arranged within the casing 29 is a helical bimetallic thermostatic element 35, the rearward end portion of which is fixedly anchored to said casing. Suitably affixed to the forward free end portion of said thermostatic element 35 is a shaft 36 which extends forwardly and outwardly through the tubular extension 33. Affixed to the outer end portion of said shaft 36, and so as to rotatably abut the outer extremity of said tubular extension 33, is a clutch-piece 37 having an interrupted peripheral flange 38 to form spaced clutch-shoulders 39 and 40. Loosely pivoted on said shaft 36 is pendant lever arm 41 which extends between the clutch-shoulders 39 and 40 of said clutch-piece 37. Said lever arm 41 is retained in assembled relation to said shaft 36 and clutch-piece 37 by a keeper member 42 and nut 43, the latter being engaged upon an outer externally threaded portion of said shaft. A split washer 44 is preferably interposed between said keeper member 42 and the pivoted end portion of said lever arm 41. Affixed to said lever arm 41, intermediate its ends, is a clip 45 adapted to embrace and carry a mercury tube contactor switch 46, which constitutes a motor control switch. The lower free extremity of said lever arm 41 is formed to provide a transverse latching tongue 47. Mounted on the panel 28 is a suitable stop means 48 which is engageable by said latching tongue 47 at proper times to limit movement of said lever arm 41.

Mounted on the extension 33 of casing 39 is a bearing plate 49 having at its inner face a bearing boss 50 of reduced diameter. The bearing plate 49 is retained in abutting relation to the outer face of the shoulder portion 30 of said casing 29 by means of a compression spring 51, washer 52 and nut 53, the latter being engaged upon an externally threaded portion of said casing extension 33. Fulcrumed on said bearing boss 50 is a carrier plate 54, an upwardly extending portion of which is provided with a clip 55 adapted to embrace and carry a mercury tube contactor switch 56, which constitutes a trip control switch. A downwardly extending arm 57 of said carrier plate 54 is provided with an outwardly projecting crank pin 58.

Supported by guide-roller means 59, which pro-

ject outwardly from the panel 28, is a longitudinally reciprocable slide-bar 60, the same being disposed beneath the above described switch assemblies. Connected with said slide-bar 60 to move therewith is an upwardly extending arm 61 having a bifurcated free end portion 62 to operatively embrace and engage said crank pin 58. Affixed to the slide-bar 60 is a downwardly yieldable spring-arm 63 having a notched latch-piece 64, which at proper times coacts with the latch-tongue 47 of the lever arm 41 by which the motor control switch is carried. Extending from said panel 28 is a depressor member or roller 65 which at proper times coacts with the spring-arm 63 to release the notched latch-piece 64 from engagement with the latch-tongue 47 of said lever arm 41.

Suitably affixed to said panel 28, below said slide-bar 60, is a switch and oil flow control means, the same comprising a cylinder 66 having an internally threaded outer end portion 67 and a diametrically reduced chambered portion 68 forming an intermediate annular shoulder 69. Located within the chambered end portion 68 is an expandable and contractible bellows member 69, having an anchor flange 70 at its outer end seated upon said shoulder 69' and clamped thereto by a clamp ring 72 which is screwed into the threaded portion 61. The forward end of said cylinder is closed by a cap-piece 73 screwed into the end of the same. Affixed to the closed free end of said bellows member 69 is a stem or rod 74 which projects outwardly through an opening 75 with which said cap-piece 73 is provided. A compression spring 76 which is interposed between the closed end of said bellows member 69 and said cap-piece 73 yieldably retains the former in normal expanded condition. Said slide-bar 60 is suitably coupled with the outer free end portion of said stem or rod 74, as e. g. by means of a coupling arm 77 affixed to said slide-bar and a coupler nut means 78 threaded on the outer end portion of said stem or rod 74. If desired, a stop sleeve 79 of suitable length to limit the contracting movement of said bellows member 69 may be engaged over said stem or rod 74 intermediate the cap-piece 73 and the free end of said bellows-member. Said cylinder 66 is provided with an inlet port 80 leading into the chambered portion 68 of cylinder 66. Connected with said inlet port 80 is an oil delivery pipe 81 leading from a motor driven oil pump (not shown), which operates to deliver oil from a source of supply to the oil-burner.

At its rearward end the cylinder 66 is provided with a reduced outlet end portion 82, to the end of which is connected a valve housing 83 having discharge passage 84 across which is disposed an apertured valve seat 85. Cooperative with said valve seat 85 is a valve member 86, the same having a stem 87 slidably supported through a channeled bushing 88 connected with the inner end of said valve housing 83. A compression spring 89 arranged between said bushing 88 and valve member 86 yieldably holds the latter seated against said valve seat 85 in closed relation to the aperture or port thereof. The stem 87 is loosely coupled with the end of the bellows member 69 by means of a coupling thimble 90 which is secured to the latter, and through the end wall 70 of which said stem 87 extends. The stem 87 has an enlarged head 91 engageable by said end wall of the coupling thimble 90. This coupling arrangement is such, that an initial contraction of the bellows member 69 can occur, before the 75

movement thereof is operative through the coupling connection, upon the valve stem 87 with consequent withdrawal of the valve member 86 from the valve seat 85 to open the aperture or port of the latter. Connected in communication with the outlet end of the discharge passage 84 is an oil delivery conduit or pipe 92, which extends into the interior of the mixing chamber or gun 5 into coupled communication with the rearward end of the burner pipe 6.

Movements of the slide-bar 60 are utilized to retract and advance the spark gap insulator means, and to this end a transverse shaft 93 is journaled in and across the mixing chamber or gun 5. One end of the shaft 93 extends outwardly through the panel 28. Affixed on the outwardly projecting end portion of the shaft 93 is a dependent lever arm 94 having a bifurcate free end portion. Fixedly secured upon the forward end portion of the slide-bar 60 is the base-block 95 of a forwardly projecting link 96 having a cross-pin 97 operatively engaged in the bifurcate end of said lever arm 94. Fixed on said shaft 93 is an upwardly extending lever arm 98 also having a bifurcate free end portion. Fixedly secured to the rearward end portion of the slide-plate 22 is a lug 99 having a cross-pin 100 operatively engaged in the bifurcate end of said lever arm 98.

Pivoted mounted on the panel 28 in a suitable location is a vertically oscillatable carrier plate 101. Affixed to said carrier plate 101 is a clip 102 adapted to embrace and carry a mercury tube contactor switch 103, which constitutes a cut-out or safety switch. Said carrier plate 101 is normally supported in an up-tilted position adapted to hold the switch 103 in a normally closed position. This is accomplished by means of a pivoted detent member 104, the dependent arm 105 of which is provided with a perforation 106 in which is normally engaged a tongue or lug 107 with which the free extremity of said carrier plate 101 is provided. Said detent member 104 is spring urged against a stop pin 108 whereby the same is disposed in the described supporting relation to said carrier plate 101. Said detent member 104 is provided with a horizontal tripper arm 109, which is engageable by means for tripping the detent member 104 to release the carrier plate 101 for gravitation to switch opening position. The tripping means comprises a cylinder 110, the interior of which is divided by a partition 111 to form an upper compartment and a lower compartment. The upper compartment is closed by a cap 112 having a bore 113 in which a plunger 114 is vertically slidable. The upper compartment is supplied with a liquid content 115 having a high coefficient of expansion when heated. The lower or inner end of said plunger 114 is exposed within the lower end of the bore 113 to engagement by said expansible liquid 115. The outwardly projecting upper end of said plunger 114 underlies the tripper arm 109 of the detent member 104. Arranged within the lower compartment of said cylinder 110 is an electrical resistance coil 116. Means is provided for manually returning said carrier-plate 101 to normal up-tilted position, the same comprising a pivoted lift lever 117 having a transverse stop pin 118 at one end to underlie the free end portion of said carrier plate 101.

The electrical circuits and connections with which the burner apparatus and the safety control means are served are shown, more or less

schematically, in Fig. 1, and are also more simply shown in Fig. 5. For convenience in connecting up the safety control devices, a suitable insulated binding-post support or base 119 is affixed to the panel 28.

Referring to Fig. 1 and to Fig. 5, the reference character 120 indicates the ingoing branch of a main service circuit leading from a suitable source of current supply, this input branch including one or more room thermostats 121 of any well known circuit make and break type adapted to be responsive to and actuated by fluctuations of temperature in the vicinity of their selected location. Said ingoing branch 120 of the main service circuit is connected to binding post A of base 119. Leading from binding post A to one pole of the cut-out or safety switch 103 is a conductor 122, and leading from the other pole of said cut-out or safety switch 103 to binding post B of base 119 is a conductor 123.

Leading from binding post B to one pole of the motor control switch 46 is a conductor 124, and leading from the other pole of said motor control switch to binding post C of base 119 is a conductor 125. Leading from binding post C to one pole of a fuel pump actuating motor M is a conductor 126, and leading from the other pole of said motor M to binding post E of base 119 is a conductor 127.

Leading away from binding post E is the outgoing branch 128 of the main service circuit.

It will be noted that the connections are such that the motor control switch 46 is in series with the safety or cut-out switch 103.

Also leading from binding post B to one pole of the trip control switch 56 is a conductor 129, and leading from the other pole of said trip control switch 56 to one pole of the resistance coil 116 is a conductor 130. Leading from the other pole of resistance coil 116 to binding post E for connection with the outgoing branch 128 of the main service circuit is a conductor 131. It will be noted that said safety or cut-out switch 103, trip control switch 56 and resistance coil 116 are connected in series.

The binding post D of base 119 is connected electrically by coupling strip d with binding post B. Leading from binding post D to one pole of the primary winding of a transformer T is a conductor 132, and leading from the other pole of said transformer primary winding to binding post E for connection with the outgoing branch 128 of the main branch circuit is a conductor 133. It will be noted that transformer T is connected in series with said safety or cut-out switch 103.

The current output of the secondary winding of transformer T is delivered to one of the ignition spark gap electrodes, as 15, by a conductor 134, which is suitably connected to the electrode 60 tail-piece 135 which extends through the electrode holder 13. The tail-piece (not shown) of the other electrode 16 is suitably connected to ground. This may be done by leading therefrom a conductor 136 having an end electrically connected to the wall of the mixing chamber or gun 5 (see Fig. 2). The tail-piece 135 of electrode 15, where passing through the chambered member 34 of electrode holder 13, is bent to by-pass around the casing 29 containing the thermostatic element 35, thus forming an intermediate secondary electrical gap, since the casing 29 is electrically grounded by reason of its connection and contact with said mixing chamber or gun 5.

When the oil burner apparatus stands idle, i. e. 75

inactive, the cold and contracted thermostatic element 35 holds shaft 36 in an anti-clockwise turned direction, thus swinging lever arm 41 to the right (as shown in Fig. 1) and thereby tipping the motor control switch 46 to a normal open position. During such idle condition of the burner apparatus, the fuel pump actuating motor M is stopped and consequently no oil is delivered to cylinder 66 so that the bellows member 69 is expanded by the spring 76. Under such conditions the rod 74 is retracted and the slide-bar 60, actuated by the bellows member 69 through said rod 74, stands likewise retracted, while at the same time the valve 86 is released to occupy its closed position under the urge of its spring 89. Retraction of the slide-bar 60 also turns the carrier plate 54, through the intermediate connections 61—62—58, so as to tip the trip control switch 56 to a normally closed position. Retraction of the slide-bar 60 also operates, through the intermediate lever arms 94 and 98, to advance the slide-plate 22 and the spark-gap insulator 25—26 carried thereby, so that the latter is interposed between the electrode terminals 19 and 20 (see Fig. 2). Under normal conditions, the safety or cut-out switch 103 is held, by the detent engaged carrier plate 101, tilted to closed condition.

When current is delivered to the control means, as e. g. by the closing of the room thermostat 121 or other corresponding means, current immediately passes through the normally closed safety or cut-out switch 103 to the primary coil of transformer T, the circuit path being closed between ingoing branch 120 and outgoing branch 128 of the main service circuit through conductor 122, closed cut-out switch 103, conductors 123, d and 132, transformer primary and conductor 133. The primary of transformer T being energized by the flow of current therethrough, the induced current output of the transformer secondary is delivered through the conductor 134 and electrode tail-piece 135 to electrode 15. Owing to the interposition of the spark-gap insulator 25—26 between the terminals 19—20 of the electrodes 15—16, the delivered energy cannot jump the ignition spark gap between said electrodes 15—16 to ground, and consequently the electrical charge in the tail-piece 135 of the input electrode 15 is diverted so as to jump the secondary electrical gap between the same and said thermostat casing 29 to ground, and the resultant arcing immediately begins to heat up said casing 29. The heat thus induced in the interior of the chambered member 34 of electrode holder 13 and transmitted to the casing 29 is in turn communicated to the contained helical thermostatic element 35. Heating of thermostatic element 35 expands the same with a torsional effect which is transmitted to shaft 36, thereby turning the latter in clockwise direction and thus moving the clutch-piece 37 in like direction so that the clutch shoulder 39 of the latter pushes against the lever arm 41 to swing the same to the left and against the stop 48, thus tilting the motor control switch to a closed position (see Fig. 3). As soon as the motor control switch closes, current is delivered to the fuel pump actuating motor M, the circuit path being closed between ingoing branch 120 and outgoing branch 128 of the main service circuit through conductor 122, closed cut-out switch 103, conductors 123, 124, closed motor control switch 46, conductors 125, 126, motor M and conductor 127.

Operation of the fuel pump, as actuated by the energized motor M, immediately delivers oil

through the delivery pipe 81 into the interior of cylinder 66 behind the expanded bellows member 69. The pressure of the ingoing oil exerts a contractive force upon the bellows member 69, which, in contracting, pushes outward the rod 74 and, through its connections with the slide-bar 60, operates to advance the latter from right to left. The forward movement of the slide-bar 60 operates, through the lever arms 94—98 to retract the slide-plate 22 and spark-gap insulator 25—26, thus withdrawing the latter from between the terminals of the electrodes 15—16 so that arcing between the latter is initiated. Owing to the loose connection provided by the coupling between the bellows member 69 and the valve stem 87, the initial movement of said bellows member 69 is not effective to open the oil discharge valve 86, until the spark gap insulator has been sufficiently retracted to permit ignition sparking between the electrode terminals. By the time this occurs, however, the slack in the coupling connection is taken up and further contracting movement of the bellows member 69 is transmitted as a pull on the valve stem 87 so that the valve 86 is pulled open against the tension of its closing spring 89. The valve 86 being thus opened, the delivered oil is allowed to flow to the burner nozzle 7 through the conduit 92 and burner pipe 6. By this arrangement a lag in the operation of the valve 86 relative to the operative withdrawal of the spark-gap insulator is provided so that igniting sparks across the electrode terminal gap are assured somewhat in advance of the moment that oil actually reaches and is discharged from the burner nozzle 7. It will be understood that air is also delivered through the mixing chamber or gun in any usual way to supply and mix with the oil sufficient oxygen to assure good and thorough combustion, as well as to direct the flame into the interior of a fire-box served by the burner.

As the slide-bar 60 is advanced it carries with it the spring supported latch piece 64 the notch of which springs over the extremity 47 of the lever arm 41 thus holding the same in forwardly swung position adapted to keep the motor control switch 46 in closed condition and uninfluenced by anti-clockwise rotation of shaft 36 under the torsional contraction of the thermostatic element 35. This is desirable, for immediately the current output of the transformer can pass to ground by jumping the gap between the electrode terminals, the heating effect upon the electrode tail-piece 135 ceases, the temperature within the chambered portion 34 of electrode holder 13 drops, and the thermostatic element 35 cools and contracts to normal initial condition.

It will be understood that the normal delivery of oil by the motor actuated pump will produce and maintain within the cylinder 66, during continued operation of the burner, sufficient pressure to maintain the bellows member 69 contracted with consequent continued maintenance of the various actuated parts of the safety control means in the several conditions assumed thereby during the starting operations.

If, in connection with the starting operations as above described, or, for that matter, at any time during progress of operation of the burner, there should occur a failure of proper functioning of the motor M or of the pump driven thereby, or a failure, through exhaustion of supply or other cause, of proper delivery of oil to and through the cylinder 66, then the oil pressure effective to maintain the bellows member 69 con-

tracted will cease, and thereupon the spring 76 will expand said bellows member. Any such expansion of the bellows member 69 will retract the rod 74 and with it the slide-bar 60. The retraction of the slide-bar 60, under such circumstances, by reason of the latched connection thereof with the lever arm 41 through the medium of the spring supported notched latch-piece 64 will immediately swing the lever arm to the right, thereby tilting the motor control switch 46 to normal open condition, thus interrupting delivery of current to motor M. As the slide-bar 60 approaches the limit of retraction, whereby it is returned to normal initial position, the spring 63 is engaged by the depressor member or roller 65, which withdraws downwardly the notched latch-piece 64 so as to release the same from engagement with the end 47 of lever arm 41, leaving the latter free to be again actuated by the thermostatic element 35 under proper conditions. The retraction of the slide-bar 60 also reversely moves the carrier plate 54 so that the trip control switch 56 is thereby returned to normal closed condition. As a consequence of the latter effect, current is delivered through the closed switch 56 to the resistance coil 116, the circuit path being closed between the ingoing branch 120 and outgoing branch 128 of the main service circuit through conductor 122, closed cut-out switch 103, conductors 123, 129, closed trip control switch 56, conductor 13, resistance coil 116 and conductor 131. Continued delivery of current through resistance coil 116 generates heat which is communicated to the expansible liquid 115, causing the latter to expand. As the liquid 115 expands it presses upon the plunger 114, causing the same to rise so as to swing upwardly the arm 109 of the detent 104, so turning the latter on its pivot as to swing the dependent arm 105 thereof out of engagement with the lug 107 of the carrier plate 101. The carrier plate 101, being no longer supported by the detent, drops downwardly thereby tilting the safety or cut-out switch 103 to open condition, thus interrupting service of current to the various switches and to the transformer T, and consequently completely preventing all further operation of the burner apparatus, until the safety or cut-out switch 103 is manually closed again. It is also to be noted that retraction of the slide-bar 60 also reversely operates the levers 94 and 96, thereby advancing the spark gap insulator means to initial interposed relation to the electrode terminals 19 and 20.

It may also be pointed out that if, during operation of the burner apparatus, there should occur a break down of the transformer T which interrupts service of sparking current to and across the electrode terminals 19-20, the burner will nevertheless continue to operate so long as oil is delivered to the burner nozzle 7, since combustion of the oil will continue, without necessity for electrical ignition, until supply to the nozzle 7 is discontinued. If, however, during such operation, the room thermostat 121 or other similar control interrupts the main service circuit, then the burner operation will be stopped and the safety control device will resume normal initial condition. If following this, the room thermostat 121 or other like control again closes the main service circuit, current will only effectively flow through the trip control switch 56 and resistance coil 116, whereby the cut-out switch 103 will be tripped and opened, and consequently oil cannot be served to the burner nozzle.

7 while the ignition system is defective or inoperative due to transformer break down or other cause.

From the above description it will be understood that the present invention provides a very effective safety control means for oil burners, the same being responsive to break downs in any phase or part of the burner operating devices so as to interrupt and prevent improper or partial operation thereof, and consequently the safety control means is well calculated to prevent risk of explosions, puff-backs or fire from oil flooding, as well as dangerous short circuits or other accidents likely to involve serious injury to the apparatus or to the furnace served thereby.

It will also be understood that many widely different embodiments of this invention could be made without departing from the scope thereof; it is therefore intended that all matter contained in the above description or shown in the accompanying drawings shall be interpreted as illustrative and not in a limiting sense.

We claim:—

1. In combination with an oil-burner apparatus having a burner nozzle, electrical ignition means including ignition spark-gap forming electrode devices, and an electric fuel pump actuating motor; safety control means comprising a retractible ignition spark-gap insulator means, an expandible and contractible thermostatic means having an electrically grounded portion disposed to form a secondary electrical gap in conjunction with the input electrode device, an initially open fuel pump motor control switch adapted to be closed by expansion of said thermostatic means, and pump supplied oil delivery means leading to the burner nozzle including means responsive to oil under pump pressure operative to retract said ignition spark-gap insulator means and to hold said motor control switch closed during normal flow of oil to said burner nozzle but to open said switch upon interruption of proper oil flow to the latter.

2. In combination with an oil-burner apparatus having a burner nozzle, electrical ignition means including ignition spark-gap forming electrode devices, and an electric fuel pump actuating motor; safety control means comprising a retractible ignition spark-gap insulator means, a torsionally expandible and contractible thermostatic means having an electrically grounded portion disposed to form a secondary electrical gap in conjunction with the input electrode device, an initially closed cut-out switch, a normally open fuel pump motor control switch in series with said cut-out switch, means actuated by expansion of said thermostatic means for closing said motor control switch, pump supplied oil delivery means leading to the burner nozzle including means responsive to oil under pressure operative to retract said ignition spark-gap insulator means and to hold said motor control switch closed during normal flow of oil to said burner nozzle but to open said motor switch upon interruption of proper oil flow to the latter, electro-mechanical trip means adapted to open said cut-out switch, said latter means including an initially closed trip control switch, and means actuated by said oil pressure responsive means to open said trip control switch during normal flow of oil to said burner nozzle but to close said trip switch upon interruption of proper oil flow to the latter.

3. In safety control means for oil-burner apparatus as defined in claim 2, manually operative

means for restoring said cut-out switch to normal closed condition.

4. In combination with an oil-burner apparatus having a burner nozzle, electrical ignition means including ignition spark-gap forming electrode devices, and an electric fuel pump actuating motor; safety control means comprising a retractable ignition spark-gap insulator means, a torsionally expandible and contractible thermostatic means having an electrically grounded portion disposed to form a secondary electrical gap in conjunction with the input electrode device, a normally closed cut-out switch, a transformer having its primary in series with said cut-out switch and its secondary connected to the input electrode device, an initially open fuel pump motor control switch also in series with said cut-out switch, means actuated by expansion of said thermostatic means for closing said motor control switch, pump supplied oil delivery means leading to the burner nozzle including means responsive to oil under pressure operative to retract said ignition spark-gap insulator and to hold said motor control switch closed during normal flow of oil to said burner nozzle but to open said motor control switch upon interruption of proper oil flow to the latter, electro-mechanical trip means adapted to open said cut-out switch, said latter means including an initially closed trip control switch, and means actuated by said oil pressure responsive means to open said trip control switch during normal flow of oil to said burner nozzle but to close the same upon interruption of proper oil flow to the latter.
5. In a safety control means for oil-burner apparatus as defined in claim 4, manually operative means for restoring said cut-out switch to normal closed condition.
6. In a safety control means for oil-burner apparatus as defined in claim 1, wherein said oil delivery means is provided with a valve initially closed against flow of oil to said burner nozzle, and a coupling connection between the oil pressure responsive means and said valve whereby the former may move the latter to open position.
7. In a safety control means for oil-burner apparatus as defined in claim 1 wherein said oil

delivery means is provided with a valve initially closed against flow of oil to said burner nozzle, a coupling connection between the oil pressure responsive means and said valve whereby the former may move the latter to open position and means to provide play between cooperative parts of said connection whereby a lag in valve opening movement occurs to permit retraction of said ignition spark-gap insulator means prior to delivery of oil at the burner nozzle.

8. In combination with an oil burner apparatus having a burner nozzle and electrical ignition means including spark-gap forming electrode devices, a spark-gap insulator means movable into and out of the gap between the electrode devices, said insulator means being of inverted T-shape in cross-section, whereby its vertical web is adapted to pass between said electrode devices while its horizontal webs are respectively adapted to pass beneath the respective terminals of the latter, and oil delivery means leading to said burner nozzle including means responsive to oil pressure operative to withdraw said insulator means from said spark-gap when oil flows through said delivery means at normal pressure and to insert the same into said spark-gap when oil pressure fails.

9. In combination with an oil burner apparatus having a burner nozzle, electrical ignition means including ignition spark-gap forming electrodes, a movable spark-gap insulator means, an electric fuel pump actuating motor, a fuel pump motor control switch, a pump supplied oil delivery means leading to the burner nozzle including spring retracted means responsive to oil pump pressure through said delivery means, and means cooperative with the pump motor control switch and spark-gap insulator means adapted to be operated by reaction of said oil pressure responsive means upon failure of oil pressure, thereby to substantially simultaneously interpose said insulator means between the spark-gap forming electrodes and open said pump motor control switch.
